UNITED STATES PATENT OFFICE

2,456,289

SAFETY DEVICE FOR AIR BOMBS

Emrik Ivar Lindman, Ronninge, Sweden

Application November 3, 1941; Serial No. 417,728
In Sweden October 7, 1940Section 1, Public Law 690, August 8, 1946
Patent expires October 7, 1960

2 Claims. (Cl. 102—7.6)

1

The principal object of this invention is to provide a very simple and reliable safety device for air bombs to prevent unintentional detonation thereof during transportation and immediately after the bomb has been thrown from the airplane.

Another object of this invention is to render it possible to release the safety device perfectly and at the right moment of time by means of a wire secured to the airplane in well-known manner, it being easily possible to adjust the safety device in such manner that the wire is drawn out in its own longitudinal direction.

Another object of the invention is to construct the safety device of few, simple and inexpensive parts, which renders it very insensitive to rough handling and causes it to function very precisely and reliably.

Embodiments of bombs in accordance with this invention are shown in the annexed drawing.

Fig. 1 shows a longitudinal section through the igniting device in the nose of the bomb having a safety device in accordance with this invention.

Fig. 2 shows a detail of the igniting device seen from above in Fig. 1.

Fig. 3 shows, on a larger scale, a section through a modified igniting device with a safety device in accordance with this invention.

Fig. 4 shows a section on the line IV—IV in Fig. 3.

Finally, Figs. 5 and 6 show modifications in views similar to Fig. 4.

Referring now to Figs. 1 and 2 of the drawings, a central tube 2, for instance of metal, extends through the whole length of the bomb which may be made of concrete.

In the tube 2 a suitable charge is arranged. For igniting this charge, either by direct shock action or by means of an igniting charge (primer or fuse) and/or an expelling charge (detonator) a firing pin 10 is arranged in the forward portion of the tube 2. In the embodiment shown, this pin is displaceably journaled in a plug 14a screwed into the front end of the tube 2, and to the pin plate 11 is secured which upon impact against the ground drives the pin 10 inwards and thus ignites the indicator charge. A safety cap 12 may be provided to protect the pin during transportation.

A safety pin 13 having an ejector spring 30 is inserted through a hole in the body of the firing pin 10 proper and abuts against the free end of the neck 14a of a plug 14 to lock the firing pin. The safety pin 13 has a hole 24 for a safety wire to be secured to the airplane. The pin 13 may

2

be turned (rotated) in two planes at right angles to each other, viz. firstly by turning the firing pin 10 in the plug 14 and secondly by turning the pin 13 around its own axis. Thus, it is always possible to turn this pin so that the hole 24 and the safety wire inserted therein is in the longitudinal direction of the wire by means of which the safety wire is secured to the airplane so that the safety wire is not subjected to any substantial bending stresses when the bomb is thrown. In other words, the safety wire may be so placed that it is extracted substantially in the longitudinal direction of the hole 24. A nut 15 serves to support the spring 16 abutting against a flange of the firing pin 10. This spring serves to keep the firing pin in its forward position during the free fall of the bomb through the air, in spite of the resistance set by the air. The firing mechanism just described is particularly suitable for heavy bombs.

The striking plate 11 which may be plane or curved, effects a perfect firing action also when the bomb strikes soft ground, water or snow.

In Figs. 3 and 4, the bomb 1 also has a plug 14 screwed into the nose end of the tube 2. The plug 14 has a channel in which a firing pin 10 moves. This pin should be very light and is connected with a striking plate 11 and also with an eye 20 for hanging the bomb vertically in the airplane. The eye 20 may be screwed into a threaded hole of the pin 10 and clamps the plate 11 to the body of the firing pin.

A spring 16 is arranged between the plug 14 and the plate 11.

Between the plug 14 and the plate 11 a safety device is normally provided which in this embodiment consists of two strips or pieces 21, 22 of sheet metal. The piece 21 is bent at 23 and into this bend one edge of the piece 22 is inserted. When the safety device is applied to the bomb, the two pieces 21, 22 are bent towards each other resiliently. Just opposite the bend 23 they are united by a headed pin 13a, which extends loosely through holes of the pieces and has a hole 24, into which a locking wire 25, for instance, a piece of piano wire, is inserted. This wire has an eye or loop 26 into which an iron wire or the like is inserted which is secured to the device for hanging the bombs in the airplane.

50 The device just described acts as follows:

For dropping the bomb the aviator extracts a bolt or the like passing through the eye 20 so that the bomb begins falling, initially with its tail foremost. Because the wire 25 is secured to the airplane, it is extracted from the hole 24,

when the bomb drops. Immediately after this, the two pieces 21, 22 spring apart automatically and are flung away from the bomb so that it is now armed with its safety device removed. It is evident that the axis of the hole 24 may be set in two planes at right angles to each other, that is to say: by turning the pieces 21, 22 on the neck of the plug 14 and also by turning the pin 13a in its hole. Consequently, it is easy to adjust the position of the hole 24 in such manner that the wire 25 is in straight line with the wire secured to the airplane and consequently is always extracted in its longitudinal direction from the hole 24, whether the bomb is hung horizontally or vertically. Consequently, the bomb may be dropped without disturbances and the wire 24 is not subjected to any substantial bending stresses, when the bomb is dropped.

In the safety device shown in Figs. 3 and 4 the pieces 21, 22 of sheet metal may be made of one integral piece 30' as shown in Fig. 5. In this case the legs of said safety piece spring apart at the release. It is also possible to arrange a separate helical spring 31 between the parts of the safety device, for instance around the pin 13a as shown in Fig. 6, to press the parts of the safety device apart at the release. In such case the parts of the safety device need not be resilient.

What I claim is:

1. In an air bomb in combination, a firing pin turnably fitting in the nose of the bomb, a striking plate on said firing pin and projecting in front of the nose of said bomb, a primer, a spring normally holding said firing pin at a predetermined distance from said primer and yielding at a predetermined minimum pressure higher than the maximum pressure effected by the air when the bomb falls through it, a safety clip comprising two flat resilient plates between said striking plate and the bomb proper, said clip having an opening formed therein extending transversely of the major planes of the flat plates, a safety pin extending through the opening in said clip, and fitting loosely therein, said clip being resilient and being under stress when assembled and tending to spring apart automatically but normally being held in safety position by said safety pin, said safety pin having a transversely extending hole therein, and a locking wire extending through said hole in said safety pin, to be extracted in its longitudinal direction out of said hole when the bomb is dropped, said firing pin and safety pin being rotatable respectively in different planes so that the hole in the

safety pin may always be in the longitudinal direction of said wire when the bomb is ready to be dropped.

2. In an air bomb, a body having an opening in its forward end, a firing pin slidably extending into said opening, spring means normally pressing said pin forwardly, a firing plate on the forward portion of the firing pin in spaced relation to the forward end of the bomb body, a safety clip rotatably engaging the firing pin between the bomb body and the firing plate, said clip having two flat parts of resilient material engaging opposite sides of the firing pin respectively with their flat sides, one of said resilient parts having a turned over end forming a recess in which an end of the other part is located when assembled, the other ends of said parts having openings formed therein, a pin having a head on one end extending through said openings, said pin fitting said openings loosely and being rotatable therein, said pin having a transverse bore extending therethrough spaced from the head, and a wire extending into said bore, the flat, resilient clip parts being resiliently deformed when assembled so as to exert pressure on each other and the pin head and wire at opposite ends and on the firing pin at their middle portions, whereby when the wire is withdrawn from the headed pin the resilient clip parts spring apart and away from behind the firing plate, thereby arming the bomb.
